W. C. Smith. Inventor

By Stephen & Campbell

Attorney's

UNITED STATES PATENT OFFICE.

MILO E. SMITH, OF BURLEY, WASHINGTON.

COLLAPSIBLE CRATE.

1,177,659.

Specification of Letters Patent. Patented Apr. 4, 1916.

Application filed September 7, 1915. Serial No. 49,275.

To all whom it may concern:

Be it known that I, Milo E. SMITH, a citizen of the United States, residing at Burley, in the county of Kitsap and State of Washington, have invented new and useful 5 Improvements in Collapsible Crates, of which the following is a specification.

This invention relates to collapsible crates, and it has for its object the provision of an 10 improved device of this nature constructed in such a manner that it may be readily folded into small compass when not in use and when open will afford a safe and secure package in which various commodities may 15 be shipped.

It is well known that it is highly desirable to provide collapsible crates of this nature because they occupy but small space during 20 the time that they are stored in a merchant's place of business, and during the time that they are in transit upon their return. Many 25 of the crates heretofore devised while being relatively cheap have been discarded after being once used.

It is an object of the present invention 30 to provide a more durable crate than those just mentioned and to construct it in such a manner that it may be readily collapsed and returned to the sender after having been 35 used, and to accomplish this in a simple and inexpensive structure so arranged that it will stand without collapsing while being filled, and will be rigid during shipment.

Further objects and advantages of the invention will be set forth in the detailed description which now follows:

In the accompanying drawing: Figure 1 is 40 a plan view of a crate in its open or unfolded condition. Fig. 2 is a side elevation thereof. Fig. 3 is a longitudinal, sectional view with the parts in open or unfolded position in full lines and folded or collapsed condition in dotted lines. Fig. 4 is a plan view of the 45 crate with the parts in collapsed condition. Fig. 5 is a detail view of the joint between the meeting ends of the top and Fig. 6 is a detail perspective view illustrating one of the hinge pintles hereinafter described.

Like numerals designate corresponding 50 parts in all of the figures of the drawing.

Referring to the drawing it will be seen 55 that the crate comprises a base 5 having up-turned side walls 6, and up-turned end walls 7. Side plates 8 are hinged to the up-turned sides 6 at 9 by means of ears 10 and pintles

11. End plates 12 are hinged to the up-turned end walls 7 by means of ears 13 and pintles 14. A partition plate 15 is hinged to the base 5 at 16, and is held in vertical position by a transverse flange 24^a formed 60 with flange 24. Cover plates 17 and 18 are hinged to the outer ends of the end plates 12 by pintles 19. The ends of the pintles 19 are provided with in-turning hooked extensions 20 adapted to engage in staple like 65 keepers 21 of the side plates 8 to hold the end walls 12 in position during the time that the crate is being filled or emptied, so that accidental collapsing of the crate will be effectively guarded against. 70

The cover plates 17 and 18 are provided with down turned flanges 22 and the end plates 12 are provided with inturned flanges 23 said flanges partly embracing the top and side edges of the side plates 8 as is clearly 75 illustrated in Fig. 2 thereby further bracing the structure and preventing the entry of dust and dirt to the interior of the crate. The cover plates 17 and 18 are provided with interengaging transverse flanges 24 and 80 25 and the flange 25 is bent to form a housing 26 for keeper bail 27. This bail extends through the housing 26, across the crate and comprises downward extensions 27^a with hooks 27^b at their terminal ends which hooks 85 pass through openings 28 in the side plates 8 when the crate is in open position.

When it is desired to collapse the crate 90 the hooks 27^b are disengaged from the openings 28 which renders it possible to disengage the flanges 24 and 25 from each other, which in turn renders it possible to lift the cover plates 17 and 18 and move the end plates outwardly so that the side plates 8 may be moved outwardly far enough for the 95 end and cover plates to be folded down into the base 5 as illustrated in dotted lines in Fig. 3; after which the side plates 8 are folded over the end and cover plates 12-17 and 18 and all of the parts are secured in 100 this folded condition by buttons 29 which are pivoted at 30 to one of the plates 8 and are adapted to be moved to engage over the edge of the other plate 8 as is best illustrated in Fig. 4. 105

While the elements shown and described are well adapted to serve the purposes for which they are intended, it is to be understood that the invention is not limited to the precise construction set forth, but that it 110

includes within its purview such changes as come within the spirit of the appended claims.

Having described my invention what I claim is:

1. A device of the character described, comprising a base, end plates hinged to said base, side plates hinged to said base, cover plates hinged at their outer ends to said end plates, the inner ends of said end plates being bent to form interengaging flanges and one of said flanges being further bent to form a bearing for a bail, a bail journaled in said bearing and comprising down-turned hooked side members, said side plates having openings formed therethrough for the reception of said hooked side members.
2. A device of the character described, comprising a base, end plates hinged to said base, side plates hinged to said base, cover plates hinged at their outer ends to said end plates, the inner ends of said end plates being bent to form interengaging flanges and one of said flanges being further bent to form a bearing for a bail, a bail journaled in said bearing and comprising down-turned hooked side members, said side plates having openings formed therethrough for the reception of said hooked side members, and a partition plate hinged to said base, the upper end of which has engagement with the flange of one of the cover plates.
3. A device of the character described comprising a base, end plates hinged to said base, side plates hinged to said base, cover plates hinged to said end plates, flanges carried by the cover and end plates which overlap the edges of the side plates, interengag-

ing flanges upon the meeting ends of the cover plates, a bail journaled in one of said flanges having down-turned hooked side members said side plates having openings formed therethrough for the reception of said hook members.

4. A device of the character described comprising a base, end plates hinged to said base, side plates hinged to said base, cover plates hinged to said end plates, flanges carried by the cover and end plates which overlap the edges of the side plates, interengaging flanges upon the meeting ends of the cover plates, a bail journaled in one of said flanges having down-turned hook side members, said side plates having openings formed therethrough for the reception of said hook members, and means carried by the end plates and detachably engaging the side plates.

5. A device of the character described comprising a base, end plates hinged to said base, side plates hinged to said base, cover plates hinged to said end plates, means for connecting the meeting ends of the cover plates, the hinged connection between the end plates, and the cover plates comprising pintles, having inturned hooked terminal ends, and keepers carried by said side plates for engaging with the inturned hooked ends of the pintles.

In testimony whereof I have hereunto set my hand in presence of two subscribing witnesses.

MILO E. SMITH.
